UNITED STATES PATENT OFFICE.

JOHN A. RATHBONE AND JOHN T. CROSSLEY, OF UTICA, NEW YORK; SAID CROSSLEY
ASSIGNOR TO SAID RATHBONE.

MOLDING-MACHINE.

No. 879,118.

Specification of Letters Patent.

Patented Feb. 11, 1908.

Application filed March 5, 1906. Serial No. 304,363.

To all whom it may concern.

Be it known that we, JOHN A. RATHBONE and JOHN T. CROSSLEY, citizens of the United States of America, both residing at Utica, in the county of Oneida and State of New York, have invented certain new and useful Improvements in Molding-Machines, of which the following is a specification, reference being had therein to the accompanying drawings.

The invention relates to molding machines in which the sand within the mold flask is compressed between opposed heads, one or both of which are provided with pattern faces.

It is the object of the present invention to provide means for positioning and embedding within the sand during the compression operation, chaplets or other members for supporting cores, chills, etc.

More particularly it is an object to provide means for holding the said chaplets or other members, so as to depend from the upper head or pattern into the flask, and for automatically releasing the same after the compression stroke, whereby they will be retained in proper position in the mold.

In the drawings, Figure 1 is a vertical section through a portion of a molding machine to which our improvements are applied; Figs. 2, 3 and 4 show various modifications of the chaplet-supporting means; Fig. 5 is a section illustrating the embedded chaplet and its holding means disengaged therefrom; Fig. 6 is a section illustrating a chaplet-supporting bearing embedded within the sand, with a chaplet resting thereupon, indicated in dotted lines; and Fig. 7 illustrates another modification of chaplet-supporting means.

Our machine is more particularly adapted for use in multiple molding in which portions of adjacent mold cavities are formed in the sand upon opposite sides of the flask by the relative movement of opposed patterns. For ordinary molding, where the pattern is placed at the bottom of the flask and the sand compacted thereabove, the chaplets are easily positioned and embedded in the sand; for instance, the end of the chaplet which projects into the mold cavity, is engaged with an aperture in the lower pattern face, and is supported with its end a fixed distance from said face, as by a chair or other support on the pattern head. The loose sand being then filled into the flask will be compacted

about the chaplet to firmly embed the same. Thus, when the pattern is removed, the end of the chaplet will be accurately positioned in relation to the face of the mold. On the other hand, in multiple molding, it is necessary to position chaplets in relation to the upper pattern as well as the lower and, as the former is movable in relation to the mold flask and may vary slightly in its final position, it is difficult to accomplish the desired result.

In the present invention this difficulty has been overcome by securing and maintaining the chaplets or other members to be embedded in fixed relation to the upper pattern face during the sand compression operation, and for then releasing the same to permit the withdrawal of the pattern.

In the construction illustrated in Fig. 1, A is the upper pattern head, B the lower pattern head, C the mold flask supported upon the lower head, and D the sand frame. E are chaplets which are positioned in relation to the lower pattern face by passing through apertures *a* therein and resting upon chairs *b* on the lower head. F are chaplets to be positioned in relation to the upper molding face, formed by the pattern on the head A. To accomplish this result, the chaplets F are detachably coupled to the upper pattern head and are arranged to depend therefrom and to be embedded in the sand during the compression thereof. The securing means employed in the construction illustrated in Fig. 1 is a series of magnets G, secured to the upper head A and having their poles in alignment with apertures *c* in the upper pattern face. Chaplets are inserted in the said apertures *c* in contact with the poles of the magnet and are held by the latter in this position. Thus, after the loose sand has been filled into the flask and sand frame, the relative movement of the heads will cause the simultaneous compacting of the sand and approach of the inner ends of the chaplets E F. These inner ends are preferably provided with enlarged heads *d*, so as to give a greater bearing upon the sand and to cause a strong compression of the thin layer of sand therebetween, the ultimate effect being to produce a rigid connection from one chaplet to the other.

In Fig. 2 is illustrated a construction in which the chaplet F' is retained in position pneumatically, its inner end abutting against a seat *e* surrounding the suction conduit *f*.

- In Fig. 3 a mechanical coupling is illustrated, comprising a light spring *g* bearing against the chaplet in a socket *h* for receiving the same. In Fig. 4, a double-pole electro-magnetic net is employed for holding the chaplet. In all of these constructions, the chaplet will be retained in fixed relation to the pattern during the compression of the sand and will then be released to permit the withdrawal of the pattern. Where the electro-magnetic construction is employed, as in Figs. 1 and 4, the releasing is effected by breaking the electric circuit and, in the construction of Fig. 2, by cutting out the suction. In Fig. 3 the tension of the spring *g* is so slight that, while sufficient to retain the chaplet in position during the sand compression, it will permit of disengagement when the chaplet is held by the resistance of the sand.
- In Fig. 5 is illustrated the pattern and magnet, after withdrawal from the sand, also showing the end of the chaplet projecting into the mold cavity.
- In Fig. 6, in place of a chaplet, a chaplet-supporting bearing *G'* is embedded in the sand, its upper end constituting a rigid bearing, upon which the chaplet *H* may be subsequently placed.
- In Fig. 7 the chaplet is supported by the engagement of the upper end thereof with a socket formed by resilient yieldable material, such as rubber *m*. This will have a slight clamping effect which will hold the chaplet in position during the sand compression, but will permit of its disengagement upon the withdrawal of the pattern.
- What we claim as our invention is:—
1. The combination with a supporting head for the mold flask, a superposed pattern and means for relatively moving the same to compact the sand against the pattern face, of means for holding a member in fixed relation to said pattern face during the operation of compacting the sand, whereby the said member is embedded in the sand.
  2. The combination with a mold flask supporting head, a superposed pattern and means for relatively moving the same to compact the sand, of means for holding a member depending from said pattern face during the operation of compacting the sand, and for releasing said member to permit the withdrawal of the pattern.
  3. In a molding machine the combination with a down-facing pattern, of means for detachably securing a pendent member thereto to embed the same within the sand.
  4. In a molding machine the combination with a down-facing pattern and means for compacting the sand thereagainst, of means for holding a pendent member in fixed relation to said pattern face during the compacting operation, and for then releasing the same.
  5. In a molding machine the combination with a down-facing pattern, of means for holding a pendent chaplet in fixed relation to said pattern face during the operation of compacting the sand, and for subsequently releasing the same to permit the withdrawal of the pattern.
  6. In a molding machine the combination with a down-facing pattern, of magnetic means for holding a member in pendent relation thereto during the operation of compacting the sand.
  7. In a molding machine the combination with a down-facing pattern, of electro-magnetic means for temporarily holding a member in pendent relation thereto during the operation of compacting the sand, and means for subsequently deenergizing the magnet to release said member.
  8. In combination a mold flask, a pattern on the lower side, a headed chaplet supported in predetermined relation to such pattern and an upper pattern face provided with a headed chaplet in line with the first chaplet, and means whereby it is secured detachably to the upper pattern.
  9. In a molding machine, the combination of a pattern and an opposed relatively movable member, and means for detachably securing to said pattern and opposed member respectively opposed headed chaplets.
  10. In a molding machine, the combination with opposed relatively movable patterns and a flask for containing the body of sand intermediate said patterns, of opposed headed chaplets detachably secured to the respective patterns and positioned thereby during the compacting of the sand.
